(No Model.)

T. JAMES.
APPARATUS FOR ROTATING CRANES.

No. 453,007.

Patented May 26, 1891.

UNITED STATES PATENT OFFICE.

THOMAS JAMES, OF BRADDOCK, PENNSYLVANIA.

APPARATUS FOR ROTATING CRANES.

SPECIFICATION forming part of Letters Patent No. 453,007, dated May 26, 1891.

Application filed September 15, 1890. Serial No. 364,963. (No model.)

To all whom it may concern:

Be it known that I, THOMAS JAMES, of Brad-
dock, in the county of Allegheny and State of
Pennsylvania, have invented a new and use-
ful Improvement in Apparatus for Rotating
Cranes, of which the following is a full, clear,
and exact description.

The mechanism heretofore commonly em-
ployed for rotating cranes has been rack-and-
pinion gearing or other positively-acting de-
vices in gear with the crane-mast. For some
purposes such prior mechanism is inconven-
ient, principally because it is permanently
connected with the crane and the crane can
only be rotated by means of it, and also be-
cause the rotation of the crane in either di-
rection is restricted to the limit of stroke
which the rotating mechanism possesses.

For the purpose of obviating the diffi-
culties above mentioned and other difficulties
with which those skilled in the art will be fa-
miliar, I have devised my present improve-
ment, which consists in combining with a
crane rotating mechanism so constructed and
connected with the crane as to turn it by fric-
tional contact. The advantage of such con-
struction is that it is less likely to break and
is more durable than positively-acting gear-
ing. It can be disconnected easily from the
crane, so as to leave the crane free to be ro-
tated by manual labor or otherwise, and it
has other advantages, some of which will be
referred to in the course of the following
specification.

The mechanism which I illustrate in the
drawings of this application I deem to be the
most serviceable and the best fitted for per-
forming the work of turning the crane, and I
therefore intend to claim it specifically herein;
but I wish it to be understood that the broad
claims of this application are not limited
strictly to mechanism of this form, but are
intended to cover the use with the crane of
frictionally-acting rotating mechanism of any
variety, in combination with mechanism for
increasing or diminishing the frictional con-
tact. Several different mechanical appliances
will be suggested to the skilled mechanic as
available for such use.

I shall now describe my invention, so that
others may make and use it, reference being

had to the accompanying drawings, forming
part of this specification, in which—

Figure 1 is a side elevation of my improved
crane-turning mechanism. Fig. 2 is a plan 55
view thereof, the top journal of the crane be-
ing shown in horizontal section. Fig. 3 is an
end view, partly in section, on the line III III
of Fig. 2.

In the drawings I show my improved rotat- 60
ing device applied to the top journal of the
crane, the mechanism being supported by
the girders of the building in which the crane
is situate. This is a good arrangement, and
is desirable for many reasons; but I do not 65
limit my invention thereto, intending to cover
it broadly as applied to the crane, whether
it be at the base or at the top.

In the drawings, 2 represents the journal
of the crane-mast, which revolves in a suit- 70
able steadiement or bearing 3.

4 is a wheel, which is fixed to the journal
and may be provided with a peripheral groove,
as shown. It is to this wheel that power is
applied for rotating the crane. 75

56 are power-cylinders, preferably operated
hydraulically, having bars 7, which project
therefrom and fit against the wheel 4 on op-
posite points of its periphery. These bars
are preferably shaped in cross-section to con- 80
form to the peripheral outline of the wheel.
As the faces of the bars and the periphery of
the wheel are not toothed, the wheel will not
be rotated if the bars be simply moved in
contact with the same unless they be held 85
against its periphery with sufficient firmness
to create the necessary friction. For the pur-
pose of creating such pressure I employ the
mechanism shown most clearly in section in
Fig. 3. On the outer side of each bar is a 90
hydraulic motor adapted to press the bar
against the wheel. This motor consists, pref-
erably, of a small single-acting hydraulic cyl-
inder 8, provided with a transverse diaphragm
9 of the proper degree of flexibility, in ad- 95
vance of which is a false or dummy plunger
10, bearing against a frame or carrier 11,
which slides on the supporting frame or cast-
ing 12 and carries an anti-friction roller 13,
which bears against the rear side of the bar. 100
The two cylinders 8 are preferably operated
by a common water supply and exhaust pipe

14, so that pressure may be applied to and relieved from both cylinders simultaneously. It will be apparent that the cylinders need only a very short stroke to perform their work 5 of pressing the bars against the wheel with sufficient force to create the necessary friction, and it is this which enables me to use the diaphragms 9.

To regulate the length to which the rollers 10 13 will be projected by an operation of the cylinders, I provide each of the latter with a lateral slot 15 in advance of the diaphragm and make the required adjustment by inserting liners through this slot between the dummy plunger and the end of the carrier 11.

It is desirable that the bars 7 should be operated simultaneously in opposite directions. For this purpose I may connect the front end of each cylinder 5 6 with the rear 20 end of the other by a common supply and exhaust pipe 16 16', so that when water is admitted to or exhausted from the front end of one cylinder it will be admitted or exhausted simultaneously from the rear end of 25 the other, and will cause the bars 7 to move simultaneously in opposite directions.

As thus constructed the operation of my improved mechanism is as follows: When it is desired to rotate the crane, I admit motive 30 fluid to the cylinders 8 through the pipe 14, and thereby I project the diaphragms 9 and the carriers 11 so as to force the bars 7 firmly against opposite points on the periphery of the wheel 4. I then admit fluid through one 35 of the pipes 16 16' and connect the other pipe with the exhaust, the effect of which is to cause the bars 7 to move longitudinally in opposite directions, so as to turn the wheel and to rotate the mast of the crane. The rotation of the mast in either direction may be 40 produced accordingly as the pipe 16 or 16' is connected with the pressure-supply. In mechanism for rotating cranes in which a toothed rack and a pinion are employed it is 45 not possible to turn the crane in one direction further than the limit of stroke of the rack. This is sometimes an inconvenience in the operation of the crane and it does not occur in the use of my invention. If after projecting 50 the bar 7 to its full extent it be desired to continue the rotation of the crane still farther in the same direction, the water-pressure may be removed from the cylinders 8, so as to relieve the bars 7 from pressure. These 55 bars may be then moved longitudinally in the opposite direction, and after being again pressed against the wheel and moved longitudinally the desired result will be attained and the rotation of the crane will be continued. This operation may be repeated as often as may be wished. If it is desired at any time to turn the crane by manual labor and not to use the hydraulic rotating mechanism, the exhaust of pressure from the cylinders 60 8 will release the bars 7 from friction against the wheels 4 and will leave the crane

disconnected from its rotating mechanism and free to be turned by hand.

Some of the advantages of my improvement have been indicated generally in the foregoing specification, and other advantages will be made apparent by use of the device. 70

One important advantage is that by dispensing with toothed gearing I obviate that liability to breakage of the turning mechanism which has occurred frequently when the chains connecting the burden to the crane break or become unfastened in any way. 75

I derive peculiar advantage from the use of two turning cylinders and bars, one bar for each side of the mast; but the mechanism may be used with but one turning cylinder and bar, if desired. It is also possible to dispense with the diaphragms in the pressure-cylinders 8 and to cause the fluid in such cylinders to act directly 80 on plungers of usual construction, though this is not so desirable, because of the necessity which it entails of packing the cylinders in order to prevent the escape of the motive fluid. 90

I claim—

1. In apparatus for rotating cranes, the combination, with the rotary crane, of a smooth-faced wheel by which the rotary motion may be transmitted to the crane, a motor having a 95 driven part adapted to bear frictionally on said wheel, and means for pressing said driven part into frictional contact with the wheel, substantially as and for the purposes described.

2. In apparatus for rotating cranes, the combination, with the crane, of a smooth-faced longitudinally-movable bar, a wheel, and mechanism for forcing the bar against the wheel, substantially as and for the purposes described. 100

3. In apparatus for rotating cranes, the combination, with the crane, of a smooth-faced longitudinally-movable bar, a wheel, and a power-cylinder 8, having a plunger bearing against the bar to move it against the wheel, substantially as and for the purposes described. 110

4. In apparatus for rotating cranes, the combination, with the crane, of a smooth-faced longitudinally-movable bar, a wheel, a power-cylinder 8, having a plunger bearing against the bar to move it against the wheel, and a roller which forms the bearing-face of the plunger, substantially as and for the purposes described. 115

5. In apparatus for rotating cranes, the combination, with the crane, of frictionally-acting mechanism for rotating said crane, a power-cylinder having a transverse diaphragm, and a plunger situated on the outside of the diaphragm and having a bearing against the frictionally-acting mechanism and adapted to apply pressure thereto to establish frictional contact, substantially as and for the purposes described. 125

6. In apparatus for rotating cranes, the combination, with the crane, of a wheel, power-cylinders 5 6, bars operated by the cylinders 130

and having opposite bearings on the wheel, and mechanism for applying pressure thereto to establish frictional contact between the bars and wheel, substantially as and for the purposes described.

7. In apparatus for rotating cranes, the combination, with the crane, of a wheel, power-cylinders 5 6, bars operated by the cylinders and having opposite bearings on the wheel, and mechanism for applying pressure thereto to establish frictional contact between the bars and wheel, the opposite ends of the respective cylinders having common fluid connections, substantially as and for the purposes described.

8. In apparatus for rotating cranes, the combination, with the crane, of a wheel, power-cylinders 5 6, bars operated by the cylinders and having opposite bearings on the wheel, and cylinders 8 8, acting on the bars to press them against the wheel, said last-named cylinders having a common water-supply passage, substantially as and for the purposes described.

In testimony whereof I have hereunto set my hand this 9th day of September, A. D. 1890.

THOMAS JAMES.
